UNITED STATES PATENT OFFICE.

WALTER C. WHITE, OF LOS ANGELES, CALIFORNIA.

TRAIN-PIPE COUPLING.

1,126,168.

Specification of Letters Patent. Patented Jan. 26, 1915.

Application filed August 13, 1912. Serial No. 714,862.

To all whom it may concern:

Be it known that I, WALTER C. WHITE, citizen of the United States, residing at Los Angeles, in the county of Los Angeles and State of California, have invented certain new and useful Improvements in Train-Pipe Couplings, of which the following is a specification.

This invention relates to automatic train-pipe couplings, and has for its object the provision of simple and efficient mechanism whereby to adequately accommodate variations in the heights of the coupling heads in the act of coupling as well as all variations incident to the movement of the cars during travel.

A further object of the invention is to provide means whereby the coupling heads will be held in proper alinement and engagement and whereby the escape of fluid between the coupling heads will be prevented.

The invention seeks to simplify the construction of automatic train-pipe couplers whereby the cost of manufacture will be reduced and the efficiency of the apparatus generally increased.

These stated objects, and such other objects as will incidentally appear from the description hereinafter given, are attained in such a device as is illustrated in the accompanying drawings, and the invention consists in certain novel features which will be particularly pointed out in the claims following the description.

In the drawings:—Figure 1 is a perspective view of a coupling head embodying my present improvements; Fig. 2 is a side elevation showing two coupling heads in engagement; Fig. 3 is a horizontal section on a larger scale, taken on the line 3—3 of Fig. 2; Fig. 4 is a longitudinal vertical section taken on the line 4—4 of Fig. 3; Fig. 5 is a detail sectional view of the ball joint employed in the train-pipe against the coupling head; Fig. 6 is a view similar to Fig. 4 showing a modification; Fig. 7 is a rear elevation of the coupling head as shown in Fig. 6; Fig. 8 is a detail perspective view of a member of the connection between the train-pipe and the coupling head; Fig. 9 is a detail perspective view of the hanger showing the parts separated but in their proper

relative positions; Fig. 10 is a detail horizontal section of a portion of one of the 55 train-pipes within the coupling head; Fig. 11 is a detail section showing the means for holding the heads in alinement; Fig. 12 is a detail view of the outer side of the air box. Fig. 13 is a detail perspective of a 60 portion of the centering device.

In carrying out my present invention, I employ a hanger consisting of straps 1 which are disposed respectively above and below the car coupling and draw bar, as shown in 65 Fig. 2, and are connected and secured to the said coupling and draw bar by bolts 2 inserted through their ends, as shown and as will be readily understood. To the forward straps 1, I secure by the bolts 2 depending 70 stirrups or U-shaped frames 3, and to the rear straps 1, I secure a back or abutment plate 4 which extends transversely beneath the draw bar and is provided with openings 5 to receive the train-pipes 6, 7, and 8 and 75 are sufficiently large to accommodate the relative movement of the pipes in coupling or uncoupling and in rounding curves, or incident to moving cars.

A brace 9 is rigidly secured to the under 80 side of the draw bar to resist endwise thrust, and this brace extends forwardly through the lower end of the abutment or back plate 4 and through the stirrup or U-shaped frame 3 by which its front end is supported, 85 said front end being deflected laterally, as indicated at 10, and then extending forwardly, as shown at 11, to constitute a shelf for supporting the coupler head.

The coupler head 12 rests upon the shelf 90 11 and lateral portion 10 of the brace and its rear end wall 13 projects beyond the stirrup or frame 3, as shown most clearly in Fig. 2. The coupler head consists of upper 95 and lower walls extending forwardly from the upper and lower edges of the rear end wall 13, the front edges of the said upper and lower walls being curved outwardly from the central longitudinal line of the coupler head, as shown at 14, to provide a 100 wide flared hood which receives the guide arm 15 of an opposed engaging coupler head. By this construction, the guide arm will be received in the hood notwithstanding 105 differences in the height of cars or lateral variations when coupling on curves. The

said arm 15 projects laterally from the central longitudinal line of the coupler head in a direction opposite to the flared portions 14 and then extends forwardly, as shown 5 clearly in Fig. 1, the several walls or faces of the guiding arm converging so that the said arm constitutes a tapered projection adapted to enter between the upper and lower flared walls of an opposing head and 10 by engaging the same guide the said heads into proper alinement.

The upper and lower walls of the coupler head are connected near the front extremity of the head by a vertical post or web 16 15 having its front face beveled outwardly and forwardly, as shown at 17, and its outer face beveled outwardly and rearwardly, as indicated at 18, to be engaged by the inner vertical face of the guide arm, so that as the 20 two coupler heads move together in opposite directions they will be shifted laterally to be brought into intimate contact. A cover or plate 19 may be secured to the outer edges of the upper and lower walls of the coupler head, so as to prevent access of dirt or other 25 foreign matter to the interior of the head and consequently avoid any clogging of any of the parts which would interfere with the successful operation of the coupler. It will 30 be noted, however, that whether this cover is or is not used, the outer side wall of the hood terminates short of the front end of the hood so that the heads may couple even when coming together at an extreme angle. 35 Disposed vertically within each coupler head, in rear of the web or post 16 and between the same and stops or ribs 20 formed on the inner surface of the upper and lower walls of the head, is an air box 21 which 40 is provided in its inner side face with ports 22 corresponding in size and location to the respective train-pipes and having fitted around the said ports elastic gaskets 23, which, when the coupler heads are together, 45 will be compressed to form fluid-tight joints between the heads. The interior of the air box is hollow and is constructed with horizontal partitions which constitute separators between the fluids conveyed through the several train pipes. The outer faces of the air 50 boxes will be engaged by the inner faces of the guide arms 15 when the two coupler heads come together and to cushion the impact of a guide arm upon an air box, I provide a spring plate 24 upon the outer wall of each air box, as clearly shown in Fig. 3. The front wall of the air box is recessed, as indicated at 25, and the end of the spring plate is turned into the said recessed portion 55 and provided with slots 26 through which securing bolts or rivets are inserted into the body of the air box to secure the plate in position, and the rear edge of the plate is secured to and under a holding strip 27

which is secured upon the outer side of the 60 box to hold the plate in its proper position and is so disposed as to prevent it projecting from the air box at such an angle as to be struck forcibly and directly by the end of the guide arm and thereby broken or bent 70 to such an extent as to be inoperative for the purposes intended. This spring plate 75 24 may be composed of several leaves, if so desired, so that the requisite strength will be obtained without unnecessary weight.

The train-pipes 6, 7, and 8 extend through the rear end wall 13 of the coupler head in the central vertical line of the same and within the coupler head they are laterally offset, as indicated at 28, so that the forward ends of the pipes may enter the rear wall of the air box. In the preferred form of the invention, the pipes are constructed in sections which are connected immediately adjacent the rear end wall of the coupler 85 head by ball joints, shown in detail in Fig. 5, and comprising a socket 29 projecting from the rear end wall 13 of the coupler head and receiving a circumferential enlargement 30 on the end of the outer section of the pipe 90 in which is fitted a similar smaller circumferential enlargement 31 on the outer end of that section of the pipe which is contained within the coupler head. By this construction and arrangement of parts, I reduce the wear upon the gasket or packing 95 32 between the members 30 and 31 and the impact is taken up by the socket 29.

Between the rear end wall 13 of the coupler head and the abutment or back plate 4 of the hanger, the train-pipe 7, containing the air for operating the brakes, is constructed with a cylinder 33 in which plays a piston 34 formed on the end of a section of the train-pipe, said section having an 100 annular shoulder 35 thereon which is adapted to impinge against the back plate 4 of the hanger when the coupler heads are brought together. The cylinder 33 is constructed with an internal annular shoulder or stop 110 36 to limit the movement of the piston 34, as shown.

The coupler heads are placed upon the shelf 11 so as to rest thereon, and, if the two cars to be coupled are of such height that 115 the coupler heads thereon remain in the same horizontal plane, the heads will rest upon the said shelves at all times. Should the heads, however, lie in different horizontal planes the guiding arms on the heads 120 engaging between the upper and lower walls or hoods of the opposed heads will cause such vertical movement thereof as will bring them into perfect alinement and cause the ports 22 of the air boxes to register exactly. 125 The vertical movement of the coupler heads will be permitted freely, as they are not secured to the hangers but merely rest there-

on, and the ball joint connections between the sections of the train-pipes will permit free movement of the said sections relative to each other in all directions, so that there will be no binding of any of the parts.

As the coupler heads come together, they will be moved laterally so as to bring the gaskets 23 into contact by the engagement of the guide arms with the beveled surfaces 18, and the relative movement of the guide arms and the opposed heads will cause the guide arms to ride upon the outer beveled walls of the air boxes so as to move the said boxes positively toward each other. After 15 the ports have been made to register the air is cut into the train-pipe 7 and will immediately flow through the same into the air boxes and to the angle cock on the adjoining car or at the end of the line. The air will 20 then be compressed against the piston 34 so that the said piston will be moved toward the rear end of the cylinder 33 and carry the shoulder or stop 35 against the abutment plate 4 of the hanger, the pressure of the 25 air then serving to hold the coupler heads longitudinally together so that the ports 22 will remain in register and the devices will be held in coupled relation and will not be liable to be accidentally uncoupled under the 30 shock of coupling additional cars to the train or while the train is rounding sharp curves or from other causes.

It will be observed that the cylinder is disposed centrally with respect to the rear 35 end wall of the coupler, so that the pressure exerted by the fluid in the cylinder will be transmitted equally to all parts of the coupler head and consequently, twisting of the head relative to the opposed head cannot 40 occur. The construction described simplifies the coupling and reduces the number of necessary parts to a minimum, so that the liability of the coupling to get out of order and necessitate frequent repairs is obviated.

45 In Figs. 6, 7, and 8, I have shown a modification of the connection between the coupler head and the cylinder by which the longitudinal disengagement of the heads is prevented. In this arrangement, instead of 50 the ball joint shown in detail in Fig. 5, I provide the rear end wall of the coupler head with the spaced lugs 37 having beveled opposed faces, as shown at 38, and between the said lugs is fitted a beveled tongue or 55 projection 39 secured in the forward end of a yoke 40 which is secured on the end of the pipe 41 projecting from the forward end of the cylinder 42. A flexible branch pipe 43 extends from the coupling or yoke 60 40 and enters the rear wall of the coupler head through an opening 44 formed therein near the side of the same. The lugs 37 and the tongue or projection 39 are pivotally connected by a pin or bolt 45 inserted

vertically therethrough, and the opening in 65 the tongue 39 should be sufficiently large to permit free play of the tongue upon the said pivot pin or bolt. Movement of the said parts freely in all directions is thus permitted, so that the heads may readily accommodate 70 themselves to variations in the position of the car or other parts during travel or in the heights of the coupler heads when being brought together. It will be noted by this construction, also, that pressure from the 75 cylinder 42 is directed against the coupler head at the center of the same, so that the coupler heads will be held positively together without any tendency to twist laterally.

To hold the coupler heads in alinement notwithstanding vertical variations of the same, I provide a centering mechanism consisting of a housing 46 secured to the lower side of the coupler head and having plungers 47 arranged therein. Plunger rods 48 extend from the said plungers through the ends of the housing and are equipped with yokes 49 adapted to engage the sides of the stirrup or U-shaped frame 3 of the hanger. 85 A closely coiled spring 50 is disposed within the housing between the plungers and bears against the same so as to hold the yokes 49 in engagement with the sides of the hanger, and the said yokes should be 90 sufficiently wide to permit longitudinal movement of the coupler heads under the impact of opposed heads, when coupling. It will be readily seen that the yokes 49 will move vertically of the hanger with the 100 coupler heads and that, if the coupler head should swing to one side from any cause, the spring will be compressed at that side toward which the coupler head swings and will re-act, by expansion, to hold the head 105 in the central line of the hanger, so that disengagement of the ports cannot occur after the heads are in coupled position and before the air is turned on.

From the foregoing description, it will 110 be seen that I have provided an exceedingly simple train-pipe coupling by which variations in the heights of the heads will be accommodated, and the coupling may be effected when the cars are on a curve, as well 115 as on a straight track. The front end of the coupling head is free from all projections which would tend to come squarely together as opposed heads approach and thereby prevent the rapid and automatic 120 coupling of the heads. The air box is housed entirely within the coupler head and is practically wedge-shaped so that the air boxes of opposed coupling heads will be moved toward each other and positively 125 held together by the engagement therewith of the guide arms.

Any convenient means may be employed

to prevent injury to the gaskets in coupling or uncoupling such, for instance, as a light spring bearing on the inner side of the air box. As the particular means employed are 5 not important, however, I have deemed illustration of the same unnecessary. Owing to the jointed construction of the train-pipes, they will move freely to accommodate variations in the heights of cars and 10 the abutment plate normally supports the device in an inclined position, as shown in Fig. 2, so that the coupler head may be raised considerably above its normal position without any liability of breaking or 15 bending any of the parts.

What I claim is:—

1. A train-pipe coupling comprising a coupler head, an air box disposed therein and provided with a port in its inner side 20 wall and having its outer side wall beveled, and a guide arm on the coupler head adapted to engage the beveled side of the air box in an opposed head.

2. A train-pipe coupling comprising a 25 coupler head having a rear wall, an air box disposed therein near the front end thereof and provided with a plurality of ports in its inner side face, train-pipes leading from the rear wall of the said air box through the 30 vertical center of the rear wall of the coupler head, and means for applying longitudinal pressure to the said rear wall of the head in the vertical plane of the train-pipes.

3. A train-pipe coupling comprising a coupler head having a post adjacent its front end, an air box disposed vertically 40 within the coupler head immediately adjacent the said post and having its outer wall beveled, a resilient cushion secured upon the outer beveled wall of said air box, and a guide arm formed on the coupler head and adapted to bear upon the cushion of an air box in an opposed head.

4. A train-pipe coupling comprising a coupler head having a rear wall, train-pipes entering said head through the rear wall thereof in the central vertical line thereof, said pipes being composed of sections 50 connected by joints which permit free relative movement of the sections, and means for applying longitudinal pressure to the rear wall of the head in the plane of the train-pipes.

5. A train-pipe coupling comprising a coupler head having a rear wall, train-pipes entering the said head, a cylinder formed on one of the said train-pipes externally to the head, a piston playing in 60 said cylinder and connected to said train-pipe, and means whereby the pressure in said cylinder may be directed centrally against the rear wall of the coupler head.

6. A train-pipe coupling comprising a

coupler head having a rear wall, an air 65 box within the head having lateral ports adapted to register with similar ports in an air box carried by an opposed head, train-pipes entering the coupler head through the central line of the rear wall of the head 70 and offset within the head to enter the air box through the rear wall of the same, and means on one of the train-pipes to exert longitudinal pressure against the rear wall 75 of the coupler head in the central vertical plane thereof.

7. A train-pipe coupling comprising a coupler head having a rear wall, a post disposed vertically in the said head adjacent the front end thereof, transverse stops 80 within the head in rear of and spaced from the said post, a laterally movable air box mounted in the head between the said post and said stops, train-pipe sections extending through the rear wall of the head 85 in the central vertical plane of the same and secured to the rear wall of the air box, and means on one of the train-pipe sections to apply longitudinal pressure to the rear wall of the head in the central plane of the 90 same.

8. The combination of a train-pipe coupler head, a shelf extending under the said head, a U-shaped frame passing under said shelf and upwardly adjacent the sides of 95 the coupler head, an abutment plate disposed in rear of the coupler head and supporting the shelf, and train-pipes passing through the said abutment plate into the coupler head, one of said pipes being provided 100 with a shoulder adapted to bear against the said abutment plate.

9. In a train-pipe coupling, the combination of a U-shaped hanger, a coupler head resting in said hanger, yokes carried by the 105 coupler head and engaging the sides of the said hanger, and means between the yokes for holding them in engagement with the hanger.

10. In a train-pipe coupling, the combination of a hanger, a coupler head resting therein, a housing secured to the coupler head, plungers mounted in said housing and carrying yokes engaging the hanger, and a spring within the housing between the said plungers and bearing upon the same.

11. In a train-pipe coupling, the combination of a coupler head having a socket on its rear end, a train-pipe fitting in said 120 socket and freely movable therein, and means for applying pressure longitudinally of the train-pipe to said socket.

12. A train-pipe coupling comprising a coupler head, train-pipe sections entering 125 said head through the central vertical plane of the rear wall thereof, ball and socket joints connecting said train pipe sections

adjacent said rear wall, and means for applying pressure longitudinally of the train-pipe through said joints against the head.

13. In a train-pipe coupling, a coupler head having a guide arm on one side and provided at its opposite side with a hood to receive the guide arm of an opposed engaging coupler head, said hood having its outer side wall terminating short of its

front end to permit coupling at an extreme angle. 10

In testimony whereof I affix my signature in presence of two witnesses.
